UNITED STATES PATENT OFFICE.

JOHANNES JACOBSEN, OF FRIEDENAU, GERMANY.

VALVE APPARATUS FOR HYDRAULIC PRESSES.

SPECIFICATION forming part of Letters Patent No. 658,915, dated October 2, 1900.

Application filed April 12, 1900. Serial No. 12,504. (No model.)

To all whom it may concern:

Be it known that I, JOHANNES JACOBSEN, engineer, a subject of the German Emperor, residing at Hauffstrasse 8, Friedenau, near Berlin, Germany, have invented a certain new and useful Valve Apparatus for Hydraulic Presses; and I do hereby declare the following to be a full, clear, and exact description of the invention, such as will enable others skilled in the art to which it appertains to make and use the same.

This invention relates to valve apparatus for controlling the action of a hydraulic press with two cylinders which receive pressure fluid alternately from a force-pump.

The invention consists, mainly, in that a piston which controls the supply and discharge of the pressure fluid to and from the press is made to work with such frictional resistance in its casing that the pressure fluid admitted behind it effects the reversal of its position as soon as the pressure of the fluid is sufficient to overcome the frictional resistance of the controlling-piston.

An arrangement of valve apparatus operating according to this invention is shown in longitudinal section on the accompanying drawing.

The pressure fluid enters the apparatus through the supply-port *a* in order to pass alternately through feed-ports *b* and *c* into the one or the other press-cylinder. The pipes *d* and *e* are exhaust-ports which serve to lead off the discharge fluid from the cylinders. In the casing there is contained in a cylindrical bore *f* a piston *g*, which has two closely-fitting ends *h* and *i*. From the feed-ports *b* and *c* pipes *k* and *l* lead to the two ends of the casing behind the annular shoulders *m* and *n* of the piston *g*. In the position of the piston shown the pressure fluid passes from *a* through the space *f* and the feed-port *b* to the one press-cylinder, while the spent fluid passes away from the other cylinder through ports *c* and *e*. From the feed-port *b* part of the pressure fluid passes through the pipe *k*, behind the shoulder *m* of piston *g*. The pressure fluid at the same time is subjected to a gradually-increasing pressure in proportion to the increasing resistance of the hydraulic press, and when this pressure has thus risen behind *m* to such an extent as to overcome the frictional resistance of the parts *h* and *i* of piston *g* this will be thereby forced over to the right hand,

and the supply-port *a* will now communicate with the feed-port *c* and feed-port *b* with the exhaust-port *d*. The pressure fluid will therefore now pass through *c* into the other press-cylinder.

The pressure behind the collars *m* and *n* can operate in the above-described manner, because the pressure transmitted from *a* to *b* or *c* operates in the space *f* equally in both directions on the piston *g*, so that such action on *g* is balanced.

In the position shown the tight fit of the piston *g* is insured by the cup-leathers *o* and *p* and in the opposite position by the cup-leathers *q* and *r*.

Having now particularly described and ascertained the nature of my said invention and in what manner the same is to be performed, I declare that what I claim is—

1. In a valve mechanism for hydraulic presses, the combination with a casing, of a piston moving in said casing with friction, a supply-port leading to the casing, feed-ports leading from the casing, exhaust-ports leading from said feed-ports to the outer ends of the casing to supply pressure to the ends of said piston.

2. In a valve mechanism for hydraulic presses, the combination with a casing, of a supply-port leading to said casing, feed-ports leading from said casing, exhaust-ports leading from said casing, a piston moving in said casing with friction and acting as a valve to place each of said feed-ports alternately in connection with the supply-port and one of the exhaust-ports, and passages leading from said feed-ports to the ends of the casing to supply pressure to the ends of said piston.

3. In a valve mechanism for hydraulic presses, the combination with a casing, of a piston having the same area at both ends and sliding in said casing with friction, a supply-port leading to the casing, feed-ports leading from the casing, exhaust-ports leading from said feed-ports to the outer ends of the casing to supply pressure to the ends of the piston.

In witness whereof I have hereunto set my hand in presence of two witnesses.

JOHANNES JACOBSEN.
